Primary Examiner — Catherine S Posthauer*Assistant Examiner* — Christine Marie Achen Zimmerman(74) Attorney, Agent, or Firm — Rankin, Hill & Clark LLP(57) CLAIM

The ornamental design for a cookware scoop, as shown and described.

DESCRIPTION

FIG. 1 is a perspective view of a cookware scoop showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The broken lines in the drawings depict portions of the cookware scoop that form no part of the claimed design.
